[57] CLAIM

The ornamental design for a weed pulling device, as shown.

DESCRIPTION

FIG. 1 is a front elevational view of a weed pulling device showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof.

The vertical shaft of the weed pulling device is shown broken away to indicate indeterminate length.

FIG.5

FIG.6

FIG.7
